UNITED STATES PATENT OFFICE

91,930

DESIGN FOR A TANK TRUCK

Henry C. French, Milwaukee, and Frederick G. Thwaits, Wauwatosa, Wis., assignors to The Heil Co., Milwaukee, Wis., a corporation of Wisconsin

Application February 9, 1934, Serial No. 50,682

Term of patent 14 years

To all whom it may concern:

Be it known that we, HENRY C. FRENCH and FREDERICK G. THWAITS, citizens of the United States, residing at Milwaukee and Wauwatosa, respectively, in the county of Milwaukee and State of Wisconsin, have invented a new, original, and ornamental Design for a Tank Truck, of which the following is a description, reference being had to the accompanying drawings forming part thereof.

In the drawings,

Fig. 1 is a side elevation;

Fig. 2 is a front perspective view; and

Fig. 3 is a rear perspective view, showing our new design.

We claim:

The ornamental design for a tank truck, substantially as shown.

HENRY C. FRENCH.

FREDERICK G. THWAITS.
